CLAIM

The ornamental design for the electrical outlet strip, as shown and described.

DESCRIPTION

FIG. 1 is a top perspective view of an electrical outlet strip;

FIG. 2 is a top view of the electrical outlet strip of FIG. 1;

FIG. 3 is a right side view of the electrical outlet strip of FIG. 1;

FIG. 4 is a left side view of the electrical outlet strip of FIG. 1;

FIG. 5 is a rear view of the electrical outlet strip of FIG. 1;

FIG. 6 is a front view of the electrical outlet strip of FIG. 1;

FIG. 7 is a bottom view of the electrical outlet strip of FIG. 1;

FIG. 8 is a top perspective view of a second embodiment of an electrical outlet strip;

FIG. 9 is a top view of the electrical outlet strip of FIG. 8, the bottom view being the same as that of the first embodiment;

FIG. 10 is a right side view of the electrical outlet strip of FIG. 8;

FIG. 11 is a left side view of the electrical outlet strip of FIG. 8;

FIG. 12 is a rear view of the electrical outlet strip of FIG. 8;

FIG. 13 is a front view of the electrical outlet strip of FIG. 8;

FIG. 14 is a top perspective view of a third embodiment of an electrical outlet strip;

FIG. 15 is a top view of the electrical outlet strip of FIG. 14, all other plan and elevation views being the same as that of the first embodiment except for the coaxial connectors;

FIG. 16 is a top perspective view of a fourth embodiment of an electrical outlet strip; and,

FIG. 17 is a top view of the electrical outlet strip of FIG. 15, all other plan and elevation views being the same as that of the first embodiment except for the circular array of perforations.
